UNITED STATES PATENT OFFICE.

JAMES J. WADE, OF CHICAGO, ILLINOIS.

SEWER-FLUSH CHECK-VALVE.

SPECIFICATION forming part of Letters Patent No. 447,387, dated March 3, 1891.

Application filed April 12, 1890. Serial No. 347,706. (No model.)

To all whom it may concern:

Be it known that I, JAMES J. WADE, a citizen of the United States, residing at Chicago, county of Cook, and State of Illinois, have invented certain new and useful Improvements in a Sewer-Flush Check-Valve, which are fully set forth in the following specification, reference being had to the accompanying drawings, forming a part thereof.

10 The purpose of this invention is to provide a check-valve, in combination with the sewer-flushing device patented to me by Letters Patent dated July 16, 1889, numbered 406,977, such valve to be adapted to serve the ordinary purpose of a check-valve in a sewer and being constructed in such manner as to be readily applied in the same fitting which contains my flushing device, and also being adapted to perform a special function in respect to said flushing device—viz., that when the flushing-stream is turned on to clear the pipe and there exists in the pipe beyond the stream such obstruction as prevents the immediate egress of the flushing-stream, causing 25 it to back up, a check-valve, being closed behind the entrance of the flushing-stream by the backing-up of the water, will permit the entire pressure of the flushing-stream—that is, the entire pressure from the water-supply—30 to be exerted to eject the obstruction from the pipe.

In the drawings, Figure 1 is a vertical section longitudinally through a portion of a sewer-drain having my flushing device, the 35 same being cut through the man-hole and ventilating-ducts. Fig. 2 is a section at the line 2 2 on Fig. 1, but with the valve removed, showing the valve-seat in the pipe. Fig. 3 is a side elevation of the removable valve-seat 40 and valve hinged thereto. Fig. 4 is a face elevation of the valve.

A is a section of a sewer, comprising a trap and having my flushing device therein, and having a man-hole opening and ventilating-opening on the two sides of the trap, respectively, and having also two check-valves, one on each side of the flushing-jet opening.

A' is the trap; A², the man-hole opening; A³, a ventilating-opening.

50 A⁴ is a flushing-jet opening.

A⁵ is a check-valve back of the flushing-jet.

A⁶ is a check-valve forward of the flush-

ing-jet and immediately below the man-hole opening.

It will be understood that the man-hole and 55 ventilating openings are adapted to be made perfectly tight at their top and at all connections, the joints being able to withstand all pressure which may be put upon them by the flushing-stream.

50 I will now describe particularly the construction of the fitting in respect to the seating and operation of the check-valves therein and the form of said valves. For the purpose of affording a seat for the check-valve in the 65 fitting A, I form an annular boss a⁵ therein, the same being shown at the seat of both of the valves A⁵ and A⁶.

I will first describe the construction by 70 which the inner valve A⁵ is accommodated in the fitting. At the vicinity of the boss a⁵, and for a distance somewhat more than the diameter of the valve—that is to say, than the interior diameter of the pipe—the fitting is extended to form a rectangular recess A⁷ at the 75 upper side of the otherwise circular duct. A valve-seat B, which may be made of brass, is formed of the shape seen most completely in Fig. 2, having the circular part adapted to fit onto the annular boss a⁵, to which it will be 80 secured by screws b, cement being employed to make its junction with the boss watertight without dressing the face of the boss or the contacting-face of the seat B. This brass seat B is extended from its circular part up- 85 ward into the rectangular recess A⁷, but not the full width or height of said recess, and at the upper corners of said rectangular extension it has the ears B' B', projecting laterally, which form the pivots of the valve. The 90 valve C is formed with lugs C' C' in form of hooks, (best seen in Fig. 3,) which fit upon the lugs B' of the seat B. The valve and seat may be dressed to make a perfect fit of their 95 contacting-faces before being inserted into the pipe and will be introduced thereinto through the man-hole and passed in horizontally at the full diameter of the pipe to reach the enlargement for the inner valve A⁵ and then turned up edgewise and placed on the 100 annular boss, whereupon the valve may be lifted and access obtained to the face of the valve-seat to insert the screws, whereby it is secured to the boss a⁵ on the pipe. When

thus in position, the valve cannot escape from the pivots B, being prevented from lateral displacement both by the sides of the pipe and by the shoulders B¹⁰ on the valve-seat, and being prevented from displacement upwardly by the upper wall A⁷⁰ of the rectangular recess A⁷. I am thus able to make a very completely fitting valve and seat in very simple form and attach it very readily to the fitting, no machine-work whatever being required upon the pipe-fitting itself. It will be observed that the corners between the annular boss a⁵ and the rectangular space of the cavity A⁷ accommodate the pivots of the valve, and that thereby there is avoided any necessity for enlarging the cavity vertically beyond the mere thickness of the valve itself, because space for the hooks C' when the valve is lifted is obtained at the sides of the circle 20 which bounds the boss a⁵. The valve A⁶ may be in all respects similarly formed and provided with a similar seat similarly secured in the pipe—that is, on the annular boss a⁵ in respect to the valve A⁵—but being located 25 immediately below the man-hole the necessity for the rectangular recess to accommodate the valve when open does not exist. The function of these two valves A⁵ and A⁶ is somewhat different, the valve A⁵ serving, 30 as already stated, to make the entire force of the flushing-jet available for forcing out obstructions, while the valve A⁶ serves the purpose of preventing foul backwater from the sewer in any event entering the flushing-pipe, 35 which being connected with the pure water-supply might, if it were open to backwater, be the avenue through which the supply would be contaminated.

I claim—

- 40 1. In combination with the sewer-pipe provided with an induction for the flushing jet or stream, a check-valve located back of the entrance of such jet and adapted to close away from the same and to open automatically with the normal flow through the sewer, substantially as and for the purpose set forth.
- 45 2. In combination with the sewer-pipe hav-

ing an induction-orifice for the flushing stream or jet directed onward in the normal direction of flow through the sewer, a check-valve 50 interposed in the sewer-pipe in advance of the flushing-jet orifice and in proximity thereto and standing normally in range of the jet ejected from the orifice and adapted to close back toward said orifice, whereby backwater from the sewer is prevented by such valve from entering the flushing-pipe and the valve is washed clean by the flushing-pipe, substantially as set forth.

3. In a sewer-pipe, a fitting A, having a 60 flushing-jet orifice A⁴ and provided with an annular boss or shoulder a⁵ back of said orifice, and a rectangular recess A⁷ upon the upper side, and a valve-seat B, adapted to be secured upon the annular boss, and the pivots B', projecting laterally in said rectangular recess, and the valve provided with the downwardly-open hooks C' C', whereby it is adapted 65 to be pivoted on said pivots B', substantially as set forth.

4. In combination with the fitting having the interiorly-annular boss a⁵, the valve-seat B, adapted to be secured upon said boss and having the lugs B' B', the valve C, having the hooks C' C', whereby it is adapted to be suspended on said pivots, said pivots projecting in the annular space included between a horizontal and two opposite vertical tangents to the outer margin of the valve-seat, the said pipe having the rectangular recess A⁷ at the 80 upper side, the height of which above the horizontal line of said pivots is less than the sum of the thickness of the valve and the diameter of the pivots, whereby the upper wall of said recess serves to retain the valve 85 on said pivots, substantially as set forth.

In testimony whereof I have hereunto set my hand, in the presence of two witnesses, this 5th day of April, A. D. 1890.

JAMES J. WADE.
